UNITED STATES PATENT OFFICE.

HARRY SEBELL, OF SOMERVILLE, MASSACHUSETTS, ASSIGNOR OF ONE-HALF TO BAB-
SON CAN COMPANY, OF BOSTON, MASSACHUSETTS, A CORPORATION OF MASSACHU-
SETTS, AND ONE-HALF TO EDWARD S. FOSTER, OF BOSTON, MASSACHUSETTS.

COVER FOR BOXES AND THE LIKE.

Application filed October 26, 1923. Serial No. 670,868.

This invention relates to a cover for boxes and the like of the type having a sight opening through the cover by means of which the contents of the box may be seen and a glass covering the sight opening.

One of the objects of the invention is to provide a cover of the above-mentioned type in which the glass may be easily and quickly removed or put in place and when once in place will be securely held there.

It is customary in covers of this type to provide a name plate carrying advertisements, etc., and the name plates are usually held in position by the glass with the result that if the glass breaks or becomes loose the name plate falls out of position. It is a further object of the invention, therefore, to removably fasten the name plate to the cover independently of the glass so that should the glass become broken or be removed the name plate will remain fixed in place.

Another object of the invention is to construct a cover in which the glass is removably held in position to cover the sight opening by shoulders formed on the flange of the cover to engage one side of the glass and movable tabs struck up from the material of the cover to removably engage the other side of the glass.

A further object of the invention is to so position the glass and the glass holding tabs that the tabs will not be broken even though they are bent back and forth a considerable number of times when changing glasses.

Other objects and features of the invention will more fully appear from the following description and the accompanying drawings and will be particularly pointed out in the claims.

The drawings illustrate in perspective, elevation and section a preferred form of construction of a cover for a box and embody the broad principles of the invention.

In the drawings:

Fig. 1 is a front elevation of the cover;

Fig. 2 is a section on line 2—2, Fig. 1;

Fig. 3 is an enlarged perspective of the glass held in position by the glass holding tabs;

Fig. 4 is an enlarged section on line 4—4, Fig. 1;

Fig. 5 is a reduced elevation of the name plate separated from the cover;

Fig. 6 is a section on line 6—6. Fig. 1;

Fig. 7 is a detail showing the position of the parts when the glass is being inserted.

As illustrated herein 1 designates a box which may be of any suitable construction.

The cover of the present invention comprises a rim portion 2 which fits over the sides of the box 1 and is removable therefrom, and a cover portion 3 hinged to the rim at 4. The cover is provided with a sight opening 5 surrounded by a ledge 6 under which lies a pane of glass 7 to close the opening. A flange 8 depends from the circumference of the ledge to properly space the cover from the rim 2. From the rim portion 2 a flange 9 extends inwardly over the edge of the box and an inner flange 10 rises from the flange 9 and is bent back upon itself to give a smooth edge in order that a person who is removing the contents of the box will not injure himself.

The present invention has to do with novel means for retaining the glass in a position covering the sight opening and means for holding the name plate 11 on the cover independently of the glass. In order to hold the glass in position, glass retaining shoulders 12 are struck up from the flange 8 to engage one side of the glass and glass retaining tabs 13 are struck up from the material of the ledge opposite the shoulders to removably engage the other side of the glass whereby the glass may be held against the ledge and cover the sight opening.

The glass retaining tabs 13 are so positioned with regard to the edge of the glass that the tabs will not be broken even though they are bent back and forth a considerable number of times when changing the glass. In order to accomplish this the side cuts 14 through the ledge from which the tabs are struck up extend under the glass and toward the sight opening such a distance that when the glass is in place and the ends 15 of the tabs are bent over the edge of the glass, the tabs are rolled into a smooth curve, as distinctly shown in full lines in Fig. 4. The glass is of such a size that the edge 16 thereof over which the tabs are bent extends partially over the tabs and thus there is no distinct bending line across the tabs so that when the tabs are opened into the position shown in dotted lines in Fig. 4, for the removal of the glass, the curve on which the tabs are bent merely enlarges. The entire

tab does not swing as on a hinge about a line across the tab as would be the case if the glass did not extend partially over the tab. It is well known that if metal is bent a few times along a line it will break at the line but if the metal is rolled into a smooth curve it may be unrolled quite a considerable number of times before there is any tendency for the metal to break. Thus by forming the tabs into a smooth curve and inserting the glass under the end of the tab, when the end of the tab is bent down over the glass and bent up again, the tab simply unrolls and there is no bending line along which the tab could break.

The shoulders 12 are struck up from the flange 8 as shown in Figs. 1 and 2 with the edge 17 farthest from the flange pressing against the glass. By using shoulders struck up from the flange and tabs struck up from the ledge to hold the glass in place the cover can be made very easily and cheaply because the sight opening and the shoulders and the tabs are all formed in one operation. The shoulders are preferably positioned with relation to the glass as shown in the drawings. When the shoulders are struck up from the flange 8, openings 18 are necessarily formed in the flange. When the glass is in position as shown in Fig. 2 the glass covers the openings 18 thereby preventing any dust or dirt from entering the box.

It will be seen that in order to allow the tabs to roll into a smooth curve and to prevent a bending line forming across the tabs it is desirable to space the glass slightly from the ledge. To keep the glass spaced from the ledge, the inner edge 19 of the ledge is bent downwardly into such a position that said edge presses firmly against the glass when it is in proper position. With the parts thus arranged the glass is prevented from rattling and is firmly secured in position covering the sight opening. As shown in Fig. 7 when the glass is placed in the cover, the edge 20 of the glass is inserted between the ledge 6 and the edge 17 of the shoulders with the edge 16 of the glass spaced from the tabs. Then the glass is brought into the final position which causes the front of the glass to press against the inner edge 19 of the ledge 6 throughout its entire length. The ends of the tabs are then bent over the edge 16 of the glass and the glass is firmly secured in place. Rattling and looseness of the glass is prevented because the inner edge 19 of the ledge 6 bears against the front surface of the glass and the shoulders 12 and the ends of the tabs bear against the rear surface of the glass. The cover is preferably made of a ductile material which has some spring to it and when it is stamped out the inner edge 19 is bent down slightly more than is

necessary so that when the glass is in final position the edge 19 is pressing against the glass with sufficient force to prevent any play.

The name plate 11 is held on the improved cover independently of the glass. For this purpose slits 21 are cut on the ledge 6, preferably at the time the cover is stamped out, and the name plate is provided with tongues 22 which project through the slits and are flattened against the under side of the ledge. To give a neat appearing box the slits 21 are so placed that when the name plate is fastened on the ledge 6 it is positioned directly over the openings 23 formed by the cutting of the tabs in order to hide the openings. Although only one name plate has been shown it is obvious that any number may be used and positioned anywhere desired on the ledge. The cover is preferably designed as shown in Fig. 1 with the sight opening a little to one side thereby leaving a name plate holding ledge 24 of substantial width at one side of the sight opening.

Having thus described the invention what is claimed as new and desired to be secured by Letters Patent is:

1. In a cover for boxes and the like, the combination with a rim to fit over the sides of the box, of a cover hinged to the rim and having a sight opening, glass retaining tabs struck up from the portion of the cover at one edge of the sight opening, and a glass closing the sight opening and extending partially over the tabs whereby the ends of the tabs may be bent over the edge of the glass in a smooth curve to hold the glass in place.

2. In a cover for boxes and the like, the combination with a rim to fit over the sides of the box, of a cover hinged to the rim having a sight opening, and a name plate holding ledge at one side of the sight opening, a name plate fastened to said ledge, glass holding tabs struck up from the material of the ledge under the name plate so as to be invisible from the top of the box, and a glass closing the sight opening and held in place by said tabs.

3. In a cover for boxes and the like, the combination with a rim to fit over the sides of the box, of a cover hinged to the rim having a sight opening, and a name plate holding ledge at one side of the sight opening, a name plate fastened to said ledge, glass holding tabs struck up from the material of the ledge under the name plate so as to be invisible from the top of the box, and a glass closing the sight opening and extending partially over the tabs whereby the ends of the tabs may be bent over the edge of the glass in a smooth curve to hold the glass in place.

4. In a cover for boxes and the like, the

combination with a rim to fit over the sides of the box, of a cover hinged to the rim having a sight opening and a name plate holding ledge at one side of the sight open-

5 ing provided with a plurality of spaced slits therethrough, a name plate fastened to the ledge by tongues projecting from said plate through said slits and flattened against the ledge, glass holding tabs struck up from the 10 material of the ledge under the name plate so as to be invisible from the top of the box, and a glass closing the sight opening and held in place by said tabs.

5. In a cover for boxes and the like, the 15 combination with a rim to fit over the sides of the box, of a cover hinged to the rim having a sight opening and a name plate holding ledge at one side of the sight opening, a name plate, tongues co-operating with 20 the ledge and the name plate to fasten the name plate to the ledge, glass holding tabs struck up from the material of the ledge under the name plate so as to be invisible from the top of the box, and a glass closing 25 the sight opening and extending partially

over the tabs whereby the ends of the tabs may be bent over the edge of the glass in a smooth curve to hold the glass in place, and the name plate is secured on the ledge independently of the glass.

30

6. In a cover for boxes and the like, the combination with a rim to fit over the sides of the box, of a cover hinged to the rim and having a sight opening, a glass closing said opening, said cover having a flange 35 around the circumference thereof, the material on one side of the flange being slit and the slit portion bent inwardly, the edge of the inwardly-bent portion engaging the glass and forming a glass-retaining shoulder, 40 glass-retaining tabs struck up from the cover on the side thereof opposite the glass-retaining shoulders, one edge of the glass extending partially over the tabs, whereby the ends of the tabs may be bent over said edge of 45 the glass in a smooth curve, thereby to hold the glass in place.

In testimony whereof, I have signed my name to this specification.

HARRY SEBELL.
